AQUAPLANE

John E. Fogelgren, 5911 Ramsgate Road, Woodacres, Md.

Filed Feb. 8, 1961, Ser. No. 63,874

Term of patent 7 years

(Cl. D71—1)

FIG.1.

FIG.2.

FIG.3.

FIG.4.

FIG.5.

FIG. 1 is a perspective view of an aquaplane showing my new design;

FIG. 2 is a top plan view thereof;

FIG. 3 is a side elevational view thereof;

FIG. 4 is a sectional view taken along the line 4—4 of FIG. 3; and

FIG. 5 is a sectional view taken along the line 5—5 of FIG. 3.

I claim:

The ornamental design for an aquaplane, as shown.
